UNITED STATES PATENT OFFICE.

EDGAR R. ALLEN, OF PRESCOTT, ARIZONA TERRITORY.

DEVICE FOR HOLDING AND COUNTING MILEAGE.

SPECIFICATION forming part of Letters Patent No. 727,871, dated May 12, 1903.

Application filed December 17, 1902. Serial No. 135,578. (No model.)

To all whom it may concern:

Be it known that I, EDGAR R. ALLEN, a citizen of the United States, and a resident of Prescott, in the county of Yavapai and Territory of Arizona, have made a certain new and useful Invention in Devices for Holding and Counting Mileage; and I declare the following to be a full, clear, and exact description of the same, such as will enable others skilled in the art to which it appertains to make and use the invention, reference being had to the accompanying drawings, and to letters of reference marked thereon, which form a part of this specification.

15 Figure 1 is a front elevation or face view of the invention, partly broken away. Fig. 2 is a partial longitudinal section of the same. Fig. 3 is a section on the line 3 3, Fig. 2. Fig. 4 is a detail side view of a portion of the 20 book or ticket *b*.

The invention relates to devices for holding and counting mileage; and it consists in the novel construction and combinations of parts, as hereinafter set forth.

25 In the accompanying drawings, illustrating the invention, the letter *a* designates the frame of the holder, and *b* the mileage-book or ticket, which is held therein by means of the bend or clamp *c* at one end of said holder.

30 At its other end the holder is provided with a chamber or recess *d* above its base, said recess opening toward the other or clamp end of the holder. This recess is provided with a top *e* and sides *f*. The top is marked with 35 dials *g* and *h*, designed to show, through the medium of the pointers *k*, the number of miles torn off from the ticket by the conductor.

A shaft *l* extends across the recess or boxing *d* and has its journals seated in the sides 40 *f* thereof. One end of this shaft is provided with a pinion *m*, which is in gear with the pinion *n* of a second shaft *p*, which is provided with a second pinion *q*, engaging a gear-wheel *r* on the first indicator-shaft, said gear-wheel having an extension or carrying arm *s*, designed to engage the large gear-wheel *t* on the second indicator-shaft at each revolution of said first indicator-shaft, such revolu-

tion having an exact relation to the circumference of the transverse shaft *l*, over which 50 the mileage-ticket is drawn. The circumference of the shaft *l* is usually sufficient to carry one section of five miles of the mileage-ticket; but it may be arranged for a larger or smaller number of miles, as may be found 55 convenient. The shafts *l* and *p* may be connected by pulleys and a small belt instead of by toothed pinions, if desirable; but the pinions are preferred, being more exact in their 60 action.

At the open side of the recess it is designed to attach to the top *e* by means of hinges a lip-piece *v*, which is held down on the ticket by means of a spring *w* with sufficient force to hold the ticket in place and allow the used 65 portion thereof to be torn off against its straight-edge *z*. When the next portion is to be taken off, this lip-piece can be raised sufficiently to enable the conductor to get hold of the end of the ticket, which can then be 70 drawn out and the used portion torn off, as above described, the lip-piece having returned to position against the ticket.

The mileage-ticket shown in connection with this device is of folded character, its 75 folds being superposed lengthwise in the holder, as indicated in the drawings. The first portion of the ticket having been passed around the transverse shaft *l*, the ticket can be drawn out as may be necessary and due 80 account kept by the indicators on the dials of the used portion thereof.

Having described this invention, what I claim, and desire to secure by Letters Patent, is—

1. The combination with mileage-ticket and a ticket-holder frame, having a clamp at one end, and a recess at the other end, of the lip-piece of said recess, a transverse shaft, dials and indicators and gearing in train with 90 such shaft and indicators, substantially as specified.
2. The combination with a ticket-holder frame, having a clamp at one end, and a recess at the other end, of a spring-operated 95 lip-piece, a transverse shaft, dials and indi-

cators, and gearing in train with such shaft and indicators, substantially as specified.

3. The combination with a folded mileage-ticket, and a holder-frame having a clamp at 5 one end, and a recess at the other end opening toward the clamp end, of a spring-operated lip-piece, a transverse shaft, dials and indicators, and gearing in train with such

shaft and indicators, substantially as specified.

In testimony whereof I affix my signature in presence of two witnesses.

EDGAR R. ALLEN.
